CLAIM

The folding knife, as described and shown.

DESCRIPTION

FIGS. 1-6 are respectively, side, bottom, front, top,
opposite side and rear views of a folding knife showing
a first embodiment of our new design in the folded
position;

FIGS. 7-12 are respectively, side, bottom, front, top,
opposite side and rear views thereof, showing the knife
in the open position;

FIGS. 13-18 are respectively, side, bottom, front, top,
opposite side and rear views of a folding knife showing
a second embodiment of our new design in the folded
position;

FIGS. 19-24 are respectively, side, bottom, front, top,
opposite side and rear views thereof, showing the knife
in the open position.
